UNITED STATES PATENT OFFICE

93,482

DESIGN FOR A TEXTILE FABRIC

Paul Klopsch, Clifton, N. J., assignor to Forstmann Woolen Co., Passaic, N. J., a corporation of Delaware

Application August 31, 1934, Serial No. 53,122

Term of patent 14 years

To all to whom it may concern:

Be it known that I, PAUL KLOPSCH, a citizen of the United States residing at 50 Heights Road, Clifton, in the county of Passaic, and State of New Jersey, have invented a new, original, and ornamental Design for a Textile Fabric, of which the following is a specification, reference being had to the accompanying drawing, forming a part thereof, in which the sole figure is a plan view of a piece of textile fabric illustrating the design.

The design comprises alternate contiguous series of parallel inclined woven stripes, the stripes of one series all being uniformly narrower than the stripes of the other series, the stripes of both series each comprising a series of joined arcuate portions having their convex sides lying in the same direction, each portion being of substantially uniform length and being irregular in width, the arcuate portions of the wide stripes

being wider in their intermediate regions than at their points of juncture, the narrow stripes having irregular points or projections extending out into the field of the wide stripes, which points are particularly prominent at the junctures of the arcuate portions of the wide stripes giving a generally bristling or crinkly effect to the design, the arcuate portions of all the stripes lying in rows of substantially uniform and equal width parallel to the direction of the stitches of the fabric which constitute the said irregular projections.

The two series of stripes are woven from yarns having different characteristics defining contrasting areas.

What I claim is:

The ornamental design for a textile fabric as shown and described.

PAUL KLOPSCH,
